UNITED STATES PATENT OFFICE.

JOHN EDWARDS, OF FENTON, COUNTY OF STAFFORD, ENGLAND.

DESIGN FOR TABLE-WARE.

SPECIFICATION forming part of Design No. 16,319, dated October 13, 1885.

Application filed June 23, 1885. Serial No. 169,600. Term of patent 7 years.

To all whom it may concern:

Be it known that I, JOHN EDWARDS, of Fenton, in the county of Staffsford, England, have invented and produced a new and original 5 Design for Table, Tea, and Toilet Ware, of which the following is a full, clear, and exact description.

Reference is to be had to the accompanying drawings, forming part of this specification, 10 in which—

Figure 1 is a plan view of the cover of a vegetable-dish illustrating my design. Fig. 2 is a side elevation of a vegetable-dish and cover. Fig. 3 is a side elevation of a tea-pot, and Fig. 15 4 is a side elevation of a cream-pitcher, these four views being deemed necessary to fully illustrate my design.

The leading features of my design consist in the sunken panels on the inclined sides, the 20 shallow rounded grooves replacing the angles and the cut-away parts in the base-flanges between the angles, and in the rectangular groove in the sides of the inclined arms and hand-pieces of the handles, the thickening at the 25 angles of the handles, and the bends in the grooves in the sides of the said thickened angles.

The dishes and covers are rectangular in

their general form, and have inclined sides with sunken middle parts or panels. The 30 angles between the sides and ends are replaced by shallow rounded grooves. The tops of the covers are flat or slightly convex. The dishes and covers have beads at or near their top edges, and the base-flanges or feet of the 35 dishes have parts cut away between their angles. The arms of the handles incline from each other slightly toward their outer ends and are connected at their outer ends by a slightly curved or angled hand-piece, and are 40 enlarged or thickened at the angles. In the sides of the handles are rectangular grooves, which have rectangular bends at the enlarged angles of the handles.

I claim—

The design for table, tea, and toilet ware, the 45 same consisting of the rectangular groove in the sides of the inclined arms and hand-pieces of the handles, the thickening at the angles of the handles, and the bends in the grooves in 50 the sides of the said thickened angles.

JOHN EDWARDS.
